UNITED STATES PATENT OFFICE.

JAMES H. ROSENTHAL AND CHRISTOPHER S. DAVY, OF LONDON, ENGLAND, ASSIGNEES
TO THE BABCOCK & WILCOX COMPANY, OF BAYONNE, NEW JERSEY, A CORPORA-
TION OF NEW JERSEY.

CHAIN-GRADE STOKER.

1,091,166.

Specification of Letters Patent. Patented Mar. 24, 1914.

Application filed June 24, 1912. Serial No. 705,424.

To all whom it may concern:

Be it known that we, JAMES H. ROSENTHAL and CHRISTOPHER S. DAVY, subjects of the King of Great Britain, residing, respectively, at London, England, and at Dulwich, London, England, have invented certain new and useful Improvements in Chain-Grade Stokers, of which the following is a specification.

- 10 This invention relates to chain grade stokers adapted to be fitted to the furnaces of steam generators and the like, and has for its object to provide an improved construction of grate in which any individual bar, 15 or set of bars, which may break or burn out, can be replaced with a minimum loss of time and labor and without the necessity for displacing any essential portion of the mechanism.
- 20 The invention will be understood by reference to the accompanying drawings in which—

Figure 1 is a part elevation, part longitudinal vertical section; Fig. 2, a top view, 25 part being in section, of two of the transverse bars on which the grate bars are suspended; and Fig. 3, a transverse section on the plane of the line 3—3 of Fig. 1.

Similar reference numerals indicate similar parts in the several views.

Referring to the drawings, the numeral 1 designates transverse bars adapted to receive and support the grate bars 2. The transverse bars are formed with a head 3 open at the sides, and the grate bars are formed with a recess 4 open at the sides, the wall of which recess corresponds to the head on the supporting transverse bar. The width of the opening 5, between the jaws 6 and 7 of the grate bars, leading into said recess is less than the diameter of the head, so that the grate bars may be assembled by sliding them endwise onto the parallel transverse bars. The grate bars are of comparatively short length and are placed, on a given bar, side by side, the heads 3 serving as pivots for the grate bars so that the latter may swing freely, one row resting upon the next adjacent row on the upper run. 50 On the lower or return run the grate bars are permitted to swing downwardly without danger of disengagement from the transverse bars, the web acting as a stop for the swinging grate bars, as shown in Fig. 1, 55 thereby providing for access of air to the

upper surface of the grate, and at the same time permitting ash to be discharged freely into the ash pit.

Although we have shown a bulbous head on the transverse bars, we do not desire to be limited to that exact form, as the invention contemplates a transverse bar having a head adapted to receive the grate bars, and grate bars having a recess, the wall of which corresponds to said head, with an opening 65 between the jaws leading into the recess which will permit assembling the grate bars in the manner above stated, and will permit their free movement on such pivotal support. 70

The transverse bars 1 are connected at their ends to endless chains 8, adapted to be driven by sprocket wheels or drums 9, disposed at or near the front and rear ends of the movable stoker frame. Rollers 10 are 75 fitted at the ends of the transverse bars 1, which rollers are adapted to run on rails or guides 11 secured to the sides of the stoker frame so as to support the upper transverse bars and grate bars. The said rollers 10 80 also serve to support the transverse bars 1 on the return, or underside of the chain forming the grate, by engaging with rails or guides 12 disposed beneath the rails or guides 11 and secured to the sides of the 85 stoker frame.

From the foregoing description it will be seen that we provide an efficient grate made up of independent sections applied on supporting bars, and wherein any of the sections, or any of the bars of a single section, may be easily removed from the supporting bar without disturbing the other sections. Also that no means of attachment of the grate bars to the supporting bars, other than the open-sided recess inclosed between the jaws 6 and 7, is necessary. 90 95

What we claim and desire to secure by Letters Patent of the United States is:—

1. A chain grade stoker comprising a plurality of transverse supporting bars having heads to receive and to prevent the grate bars being disengaged, and grate bars each having an open recess the wall of which corresponds to said head, and the opening 100 thereinto of less width than the diameter of the head but of sufficient width to permit swinging of the grate bars on the supporting bars. 105
2. A chain grade stoker comprising a plu- 110

- rality of transverse supporting bars having heads to receive and to prevent the grate bars being disengaged, and grate bars each having open jaws and a recess between said jaws open at the sides and corresponding to said head, the opening into said jaws being of less width than the diameter of the head but of sufficient width to permit swinging of the grate bars on the supporting bars.
- 10 3. A chain grate stoker comprising a plurality of transverse supporting bars each having a bulbous head, and grate bars having an open-sided recess corresponding to the head, the heads on the supporting bars preventing the grate bars from being disengaged therefrom but permitting the grate bars to be slid endwise thereon and to swing on said heads as a pivot.
- 15 4. A chain grate stoker comprising a plurality of transverse supporting bars each having a web and a head, and grate bars adapted to be assembled on the heads of said transverse bars and to swing thereon, the webs acting as stops for the swinging grate bars on the return run of the grate.
- 20 5. A chain grate stoker comprising a plurality of transverse supporting bars each having a head and a web, and grate bars each having open jaws and an open sided recess between the jaws corresponding to 30 said head, the opening into the jaws being of less width than the diameter of the head, whereby the grate bars may be slid endwise over a transverse bar and may swing on said head, the web acting as a stop for the 35 swinging grate bars on the return run of the grate.
6. A chain grate stoker comprising a plurality of transverse supporting bars each having a web and a bulbous head, and grate bars each having open jaws, and a recess between said jaws open at the sides and corresponding to said head, the opening of the jaws being of less width than the diameter of the head, whereby the grate bars may be 40 slid endwise over a transverse bar and may swing on said head, the web acting as a stop for the swinging grate bars on the return run of the grate.

In testimony whereof we have hereunto 50 signed our names in the presence of two subscribing witnesses.

JAMES H. ROSENTHAL,
CHRISTOPHER S. DAVY.
